(57) CLAIM

I claim the ornamental design for an ear-protective covering, as shown and described.

DESCRIPTION

FIG. 1 is a perspective view of a ear-protective covering showing my new design;

FIG. 2 is a front elevational view thereof;

FIG. 3 is a top plan view thereof;

FIG. 4 is a rear elevational thereof; and,

FIG. 5 is a side view thereof.

The crosshatch shading shown in broken lines forms no part of the claimed design.
